UNITED STATES PATENT OFFICE.

ABRAHAM PODEL, OF LONG ISLAND CITY, NEW YORK, ASSIGNEE TO ANCHOR CAP & CLOSURE CORPORATION, OF LONG ISLAND CITY, NEW YORK, A CORPORATION OF NEW YORK.

SHEET-ALIGNING DEVICE.

Application filed July 7, 1925. Serial No. 41,924.

The present invention relates to sheet aligning devices and more particularly to a device for aligning sheets of metal such as tin and the like.

5 An object of the present invention is to provide a sheet aligning device readily applicable to lacquering machines, ovens and the like which will accurately position the sheets of tin or other material without interfering with the usual operation of such machines.

Another object of the invention is to provide a pair of sheet engaging members interconnected to cause said members to engage 15 sheets alternately on opposite edges thereof, thereby to position correctly the individual sheets as they pass on a suitable conveyor without occasioning buckling of the sheets by the application of pressure on opposite edges simultaneously.

A further object of the invention is to provide an aligning device adapted to position sheets having a maximum variation from the desired position with a minimum 25 degree of movement of the sheet engaging member; to effect such a result by means of the shape of the ends of the engaging members first to contact with the approaching sheets whereby the distance between these ends is substantially greater than the 30 distance between the other portions of the members so that the sheets which are furthest from their correct position are moved in successive steps to their correct position.

35 Further objects of the present invention contemplate a device of the above characteristics which is positive in action, and which is of such simple and rugged construction as to insure its proper operation 40 under all conditions commonly encountered in this class of work.

Other and further objects of the invention will be obvious upon an understanding of the illustrated embodiment about to be described or will be obvious from the accompanying drawings or indicated in the appended claims; and various advantages secured by the invention other than those hereininafter specifically referred to will occur to 45 one skilled in the art or become evident upon the employment of the invention in practice.

A preferred form of the invention has

been chosen for purposes of description and is shown in the accompanying drawings 55 wherein like characters refer to similar parts throughout.

Fig. 1 is a front elevational view of the device;

Fig. 2 is an end elevational view of the 60 device with certain parts broken away to simplify the drawing;

Fig. 3 is a cross sectional view on the line 3—3 of Fig. 2;

Fig. 4 is a cross sectional view along the 65 line 4—4 of Fig. 2;

Fig. 5 is a top plan view of a portion of an oven showing a conveyor and associated mechanism with the present invention applied thereto; and 70

Fig. 6 is a side elevational view of the mechanism shown in Fig. 5.

In the manufacture of containers, covers and other articles from sheet metal or the like, it is customary to lacquer the sheets 75 and to apply any ornamental designs or advertisements thereto prior to their being stamped and formed into the desired articles. Since many identical designs are applied to the same sheets, and since in many instances it is necessary to run the sheets through several machines where frequently one design is superimposed on another, it 80 is necessary that the sheets pass through the machine in accurate position. This is particularly true where several colors of lacquer or paint are used in the design or advertising matter imprinted thereon.

The most common form of device for aligning sheets prior to their entry to such 90 machines are metallic rods placed on the opposite sides of the conveyor disposed at an angle to the line of movement of the sheets approaching the machines being fed so that the respective sheets, if out of alignment, will be engaged by these members and forced into position. The pressure required for the alignment of the sheets with a device of this character is excessive and frequently causes the sheets to buckle since the pressure is applied at an angle to the plane of the sheets and not in the plane of the sheets. Furthermore, if the sheets vary from the standard size the larger sheets may have to buckle in order to pass between the aligning member. 100 105

The present invention eliminates the difficulties encountered heretofore by providing a sheet aligning device in which there is a pair of horizontal members between 5 which the sheets are adapted to pass edge-wise disposed thereto and these members are interconnected so that when reciprocated they engage the opposite edges of the sheets alternately and move them into their 10 correct positions. All forces are applied to the edges of the sheets and in the plane of the sheets. The buckling of oversized sheets is eliminated since they are free to move under the action of either of the positioning members because the members engage the opposite edges of the sheets alternately. The present device is adapted to align sheets which vary from their correct position on a conveyor a maximum amount, 15 since the positioning members are reciprocated toward and away from the respective sheets.

Referring more particularly to the drawings, there is shown a pair of base members 25 1 and 2, which may for convenience be a part of the machine to which the device is attached, or they may be secured to a suitable foundation adjacent a conveyor. Suitable extensions or supporting members 4 and 5 are bolted at their lower ends to the members 1 and 2, respectively and have their upper ends pivotally secured to the center portion to a pair of upright members 30 6 and 7. The upper ends of the upright members have suitable sleeves formed therein adapted to accommodate a pair of arms 8 and 9 which are held in position by the bolts 10 and which likewise have sleeves formed at their ends to accommodate the sheet engaging members 14 and 15 securely held in position by the bolts 16. The lower ends of the upright members are pivotally connected to the rod 17 which correlates the movements of the sheet engaging members 35 so that the opposite edges of the respective sheets are engaged alternately thereby.

The supporting member 4 is extended beyond and downwardly from the pivot 18 until it is substantially U-shaped, and suitable bearings 20 and 21 are formed in the legs of the U to accommodate a shaft 22 extending therebetween. A cam 24 is mounted on the shaft 22 and is adapted to engage a cam follower 26 mounted on the lower end of the upright member 6 and held in contact with the cam by means of the spring 28 attached to the upright member 7 and support 5. The rotation of the shaft 22 oscillates the upright members and the sheet engaging members 14 and 15 by means of the cam 24 to properly position the sheets. A gear 30 on shaft 22 meshes with 40 gear 31 on shaft 32 to rotate the cam and

to operate the device. The shaft 32 may be mounted in suitable bearings 34 on the members 1 and 2 and may be operatively connected to a driving mechanism through the gear 36 thereon.

It will be noted that the sheet engaging members 14 and 15 are bent outwardly to afford a greater distance between the forward ends thereof than between the other portions of the members. The reason for 70 this is to accommodate sheets varying from their correct position a considerable amount. Such sheets will be engaged by the flared ends of the members 14 and 15 and pressed inwardly by successive engagements of 75 these members therewith, until the sheets are sufficiently near their correct position to be aligned by the straight portions of the members 14 and 15. In this way sheets may be positioned without any tendency 80 to buckle them.

In Figures 5 and 6 of the drawings, the present invention is shown applied to the delivery end of an oven 40 from which sheets are about to be transferred to the conveying mechanism 41 and to the lacquering machine 42. The oven 40 comprises generally a conveyor 44 having U-shaped supporting wires 45 adapted to convey metallic sheets in an upright position past the sheet engaging members 14 and 15 of the sheet aligning device which is designated as a whole by 39. After being aligned, the sheets are laid flat upon the conveyor 41 which delivers them to a suitable lacquering machine. Both the conveyor and the sheet positioning device are actuated by the gear 36 operatively connected to the motor 43 through the worm gear 46, shaft 47, gears 48 and 49 and shaft 50. The sheets resting upon the supporting members 45 are engaged by the reciprocating positioning members 14 and 15 and pressed into correct alignment prior to their delivery to the conveyor 41 and as a result they reach the machine 42 in correct alignment, 90 and each sheet is in position to receive designs or advertising matter in predetermined rotation to other designs thereon or to the edges of the sheets.

A more detailed description of the apparatus shown in Figs. 5 and 6 may be found in applicant's prior application, Serial Number 744,340, filed October 18, 1924, of which the present application is a continuation as to all common subject matter.

While the preferred embodiment of the invention is described in detail with reference to the drawings herein, it is not intended to limit the invention to the present disclosure, as many changes can be made without departing from the spirit of the invention, and therefore the description is to be taken as illustrative and not in a limiting sense, as the scope of the invention is defined in the claims.

Having thus described my invention, what I claim is:—

1. In a device of the class described, a device for aligning sheet material comprising supporting members, a pair of arms pivoted to said members, means to transmit motion from one arm to the other, means on said arms for engaging the edges of sheets, a cam follower mounted on one of said arms, 10 and a cam in engagement with said follower for reciprocating said engaging means.

2. In a device of the class described, a device for aligning sheet material comprising a pair of supporting members, a pair of arms pivoted to said members, means for transmitting motion from one arm to the other, means on said arms for engaging the edges of sheets, a cam follower mounted on one of said arms, and a cam in engagement with 20 said follower for reciprocating said engaging means to engage opposite sides of said sheets alternately.

3. In a device of the class described, a device for aligning sheet material comprising 25 supporting members, a pair of arms pivoted on said members, means for transmitting motion from one arm to the other, one of said supporting members being U-shaped, a pair of bearings in said U-shaped member, a shaft mounted in said bearings, means for rotating said shaft and a cam thereon for reciprocating said arms.

4. In a device of the class described, a device for aligning sheet material comprising 30 supporting members, a pair of arms pivoted to said members, means for transmitting motion from one arm to the other, means on said arms for engaging the edges of sheets, one of said supporting members being 40 U-shaped, a pair of bearings in said U-shaped member, a shaft mounted in said bearings, means for rotating said shaft and a cam thereon for reciprocating said arms to operate said engaging means.

5. In a device of the class described, a device for aligning sheet material, comprising a pair of supporting members, a pair of arms pivoted on said members, a bar connecting the lower ends of said arms, one of 50 said supporting members being U-shaped, a pair of bearings in said U-shaped member, a shaft mounted in said bearings, means for rotating said shaft, and a cam thereon for reciprocating said arms.

6. In a device of the class described, the combination of a U-shaped supporting member having bearings therein, a shaft mounted in said bearings and extending across said supporting member, a cam on said shaft, a 55 second member pivoted to the U-shaped member adapted to engage the edges of the sheet to position same, and a cam follower attached to said second member to cooperate with said cam to oscillate said second member.

7. In a device of the class described, the combination of an inverted U-shaped supporting member having bearings in the lower ends thereof, a shaft mounted in said bearings and extending across the open portion of said U-shaped member, a sheet engaging member pivoted to the upper portion of said supporting member, and a cam on 70 said shaft adapted to engage and oscillate said sheet engaging member. 75

8. In a device of the class described, the combination of an inverted U-shaped supporting member having bearings in the lower ends thereof, a shaft mounted in said bearings and extending across the open portion of said U-shaped member, a sheet engaging member pivoted substantially at its center to the upper portion of said supporting member, a cam follower on the lower portion of said sheet engaging member 80 extending below the pivot, a cam on said shaft adapted to engage said cam follower to oscillate said sheet engaging member. 85

9. In a device of the class described, the combination of a pair of supporting members, a pair of vertical members pivoted at their central portions to said supporting members, a pair of horizontal members attached to said vertical members to engage the edges of sheets and position same, a rod joining the lower ends of said vertical members, and means for reciprocating said horizontal members. 90 95

10. In a device of the class described, the combination of a conveyor for sheet material, a pair of vertical members pivoted substantially at their center portions, a pair of horizontal sheet engaging members mounted on the upper ends of said vertical members, a rod joining the lower ends of said vertical members to correlate the movement thereof, and means for reciprocating said sheet engaging members to position sheets on said conveyor. 100 105

11. In a device of the class described, the combination of a conveyor adapted to support a series of sheets of tin in vertical position, a pair of vertical members pivoted substantially at their center portions, a pair of horizontal sheet engaging members mounted on the upper ends of the vertical members, a rod extending below the portion of the conveyor supporting the sheets and joining the lower ends of said vertical members to correlate the movement of the latter, and means for reciprocating said sheet engaging members to position sheets as they are moved past said members by the conveyor. 110 115

12. In a device of the class described, the combination of a pair of upright sheet engaging members, means for pivoting said members substantially at their central portions, a rod connected to the lower ends of the vertical members to form therewith an 120 125 130

open sided rectangular construction, means for conveying sheets of material through the upper portion of said rectangular construction, and means for oscillating the upright members to position the sheets on the conveying means.

13. In a device of the class described, the combination of a pair of upright members, a pair of horizontal members mounted at the upper ends thereof to engage sheets, supporting means pivoted to said upright members substantially at their central por-

tions, a rod pivotally connected to the lower ends of the upright members to form a substantially open sided rectangular construction, a conveyor for moving sheets of material through the open portion of said rectangular construction, and a cam for oscillating the upright members to bring said horizontal members into engagement with the sheets on the conveyor to position same. 15 20

ABRAHAM PODEL.
